UNITED STATES PATENT OFFICE.

GUSTAV FOGDE, OF HOQUIAM, WASHINGTON.

SAW.

1,401,529.

Specification of Letters Patent. Patented Dec. 27, 1921.

Application filed January 2, 1920. Serial No. 348,984.

To all whom it may concern:

Be it known that I, GUSTAV FOGDE, a citizen of Finland, residing at Hoquiam, in the county of Grays Harbor and State of Washington, have invented certain new and useful Improvements in Saws, of which the following is a specification.

This invention relates to improvements in hand saws for work in shops, ship yards, and for other purposes and its object is to provide a device of this class that may be driven by compressed air or by other suitable means. A further object is to provide a device of this class that is very simple in construction and operation and consequently cheap to manufacture. With the foregoing and other objects in view the invention consists in the combination and arrangement of parts to be hereinafter fully described, pointed out in the appended claim and illustrated in the accompanying drawing which forms a part of this specification and in which—

Figure 1 is a sectional view of the device in front elevation.

Fig. 2 is a section on line 2—2 of Fig. 1.

Like reference characters denote corresponding parts in both views.

The reference numeral 1 denotes a casing 30 formed with the partition 2, with the intake extension 3, the exhaust port 4 and with the saw-carriage-chamber 5. Journaled in one wall of the casing and in the partition 2 is the axle 6 upon which the rotor 7 is made 35 fast and likewise the disk 8, said disk and rotor being arranged upon opposite sides of the partition 2. The rotor is formed with the blades 9 which are driven by compressed air from the intake 3, the air then 40 passing out through the exhaust 4. Air is introduced into the intake through the air pipe 10, the air being regulated or controlled by the air valve 11 having the air passage 12, said valve being yieldingly retained with 45 its air passage out of register with the passage in the intake through the medium of the

expansion spring 13 arranged in the seat 14^a formed in the intake. The passage of air through the intake is permitted by manual depression of the hand lever 14 from its position in full lines, Fig. 1, to the position shown dotted, said hand lever being fulcrumed to the handle 15 and one end of said lever engaging the said air valve. A rib 15^a formed in a recessed portion 15^b of the handle limits the outward movement of the heel of the lever 14 thus preventing this member from moving out of operative engagement with the valve 11.

The disk 8 is connected off center, by the piston 16, to the saw carriage 17 that operates in the saw-carriage-chamber and that carries the saw blade 18. The entire saw is of light weight and easily moved from place to place by its handles 15, 19 the latter being secured to the saw-carriage-chamber. The saw is put in motion by manual depression of the hand lever 14 and the blade 18 then applied to the work.

What is claimed is:

A sawing tool comprising a cylindrical casing having a central partition therein to provide chambers at each side thereof, a rotor in one of said chambers, a disk in the other of said chambers and carried by said 70 rotor, a saw guide on said casing, a saw 75 slideable in said guide, crank and pitman connection between said saw and disk, an air inlet stem on said casing, an exhaust port in said casing, said stem and port communicating with the rotor chamber, a valve in said inlet stem, a handle on said stem, and valve operating means carried by said handle.

In testimony that I claim the foregoing 85 as my own I have hereto affixed my signature in the presence of two subscribing witnesses.

GUSTAV FOGDE.
